RECORD CHANGER MECHANISM

Rudolph A. Beowar, Chicago, Ill., assignor to Galvin Manufacturing Corporation, Chicago, Ill., a corporation of Illinois

Application June 13, 1941, Serial No. 397,944

12 Claims. (Cl. 74—1)

This invention relates generally to a phonograph for automatically playing a plurality of records in succession and in particular to the record changing means for such phonograph.

It is an object of this invention to provide improved record changing means for an automatic phonograph.

Another object of this invention is to provide for an automatic phonograph improved record changing mechanism which is completely mechanically operated.

Yet another object of this invention is to provide record changing mechanism having improved means for operating a record releasing unit including a rotatably supported eccentric record ejector portion.

A further object of this invention is to provide improved record changing means having a clutch unit adapted for operative engagement with a continuously rotating driving member and selectively operated by mechanically actuated means to positively control the operating cycle of the record changing means.

Another object of this invention is to provide improved record changing mechanism which is simple in design, compact and rugged in construction, comprised of a minimum of parts requiring adjustment, and efficient and positive in operation.

A feature of this invention is found in the provision of a record releasing unit having an oscillating ejector portion which is in driven engagement with a rotatable cam member directly through an oscillated operating arm.

Yet another feature of this invention is found in the provision of record changing means having a clutch unit selectively engageable with a continuously rotating member and mechanically actuated by spring tensioned means to define the cycle of operation of the record changing means.

A still further feature of this invention is found in the provision of record changing means for an automatic phonograph having rotary cam means in continuous engagement with a friction gear adapted to be pivotally moved into and out of frictional engagement with a continuously rotating driving member, with the operating positions of the friction gear being selectively determined and retained by means including a pair of pivoted and relatively movable control members, yieldably connected together for cooperative action, and operatively associated with the rotary cam means and tone arm for the phonograph so as to be responsive in operation to the relative position of such latter two elements.

Further objects, features, and advantages of this invention will become apparent from the following description when taken in connection with the accompanying drawings in which:

Fig. 1 is a plan view of the record changing means of this invention in its assembled position in a phonograph with parts of the phonograph being removed for clarity;

Fig. 2 is a fragmentary diagrammatic plan view of the clutch unit for the rotary operating cam means;

Fig. 3 is illustrated similarly to Fig. 2 and shows parts thereof in a changed position;

Fig. 4 is a fragmentary sectional view taken along the line 4—4 in Fig. 2 showing the assembly for relative movement of the actuating arms for the clutch unit;

Fig. 5 is a plan view showing the assembly of a modified form of actuating arms for the clutch unit;

Fig. 6 is a sectional view as seen along the line 6—6 in Fig. 5;

Fig. 7 is a front view partly in section showing the complete assembly of the record releasing means;

Figs. 8 and 9 are fragmentary views of the record releasing means illustrated similarly to Fig. 7 and showing changed positions of parts thereof;

Fig. 10 is a fragmentary sectional view taken along the line 10—10 in Fig. 7;

Fig. 11 is a fragmentary plan view of an edge support for the records to be played;

Fig. 12 is a bottom view of the single operating cam used in the record changing mechanism;

Fig. 13 is a sectional view taken along the line 13—13 in Fig. 12;

Fig. 14 is a fragmentary sectional view showing the assembly relation of the operating cam and tone arm; and

Fig. 15 is a plan sectional view as seen along the line 15—15 in Fig. 14.

The record changing means of this invention is illustrated with a phonograph having a stack of unplayed records supported above the turntable at their centers on a tubular stationary centering pin extending upwardly from the turntable, and at their rims on an edge support. A record ejecting unit having an eccentric oscillating ejector portion for successively releasing the unplayed records into a playing position, is rotatably mounted in the stationary centering pin, with a portion thereof extending below the turntable for operative engagement with a segmental gear portion formed on one end of an

operating arm, the opposite end of the arm being operatively associated with a rotary cam which is adapted to oscillate the segmental gear portion to in turn operate the record ejecting means. The tone arm for the phonograph is also operated by the rotary cam in a predetermined sequence relative to the record releasing means. The rotary cam, during the playing of a record, is stationary and is rotated through substantially a complete revolution, when a record is being changed, by means including a friction gear in continuous operative engagement therewith and arranged for pivotal movement into and out of an engaging position with the phonograph turntable. A selective pivotal movement of the gear into and out of an engaged position with the turntable is accomplished by mechanical actuating means operatively associated with both the rotary cam and the tone arm to define the angular displacement of the cam and hence a complete cycle of operation of the record changing mechanism.

With reference to the drawings, there is shown in Figs. 1 and 7 an automatic phonograph including a top or mounting plate 15, having a turntable 16 rotatably supported thereon as by a bearing unit 17. The turntable is driven by a motor 18 having a control switch 14 located on the top plate 15 and including a rubber gear 19 on the shaft thereof in frictional engagement with a rubber gear 21, which in turn is in frictional engagement with the inner periphery of the rim 22 of the turntable for driving the same. The stack of records 23 to be played are supported directly above the turntable by means including a stationary centering pin or member 24 which is mounted on the top plate 15 by supporting means designated generally as 26, and extends upwardly from the turntable, the bearing unit 17 being positioned about the supporting means 26.

As shown best in Fig. 7, the centering member 24 is of tubular construction and has fitted therein at its upper end a bearing member 27 having a reduced portion inserted within the centering pin, and a body portion extending upwardly from the top of the pin and concentric therewith. The bearing 27 is formed axially thereof with an eccentric bore for receiving therein a record ejector unit comprising a tubular stem or shank 28 having its upper end 29 projecting upwardly from the bearing member 27, and its lower end 31 extended through the centering pin 24 and supporting means 26. Thus as is clearly evident in Fig. 7 the tubular stem 28 is rotatably supported at its upper end 29 in the bearing 27 and at its lower end 31 in the post supporting means 26. An eccentric ejector portion 33 is mounted on the tube 28 above the member 27 so as to be moved into and out of a position concentric with the enlarged portion of the bearing member 27 and hence with the centering pin 24 on rotation of the tube 28. A pinion gear 32 in operative engagement with an operating arm 25 is mounted at the end 31 for a purpose to be later fully described.

The tubular stem 28 of the record ejector unit in turn rotatably supports therein a pin or axis member 34 which extends completely therethrough. An eccentric cap member 36 is mounted on the upper end of the pin 34 for concurrent movement with the pin, the lower end of the eccentric cap or sleeve 36 having a cavity 38 therein adapted to fit over the upper end of the tube 28, this construction serving to facilitate

the assembly of the eccentric cap relative to the centering pin 24 and the ejector portion 33. By virtue of the rotatable support of the pin 34 in the tubular stem 28 of the ejector unit, the eccentric cap is movable into and out of a position concentric with the centering pin 24, these positions being defined by means now to be described.

The lower projecting end 39 of the pin 34 is of flat form (Figs. 7 and 10) and positioned between 10 a pair of spaced flat spring members 41 which are secured to a mounting bracket 42 supported from the top plate 15. On engagement of the 15 flat sides of the end portion 39 with the inner sides of the spring members 41, the pin 34 is releasably locked against further rotation. These 20 releasable locking positions, of course, occur substantially 180 degrees apart, and correspond to the two operating positions of the eccentric cap 36.

When the cap 36 is positioned out of concentricity with the pin 24 the stack of records 23 positioned thereabout are aligned for support at their centers on the ejector portion 33, which portion is normally positioned concentric with the 25 pin 24. These relative positions of the cap 36 and ejector portion 33 are shown in Fig. 7. The records 23 are further supported at their edges by an edge support or pedestal (Fig. 11) having a record supporting ledge 44 mounted on, but offset relative 30 to a shaft 46 which is rotatably supported on the mounting plate 15 and will be later noted. The ledge 44 is rotatable through substantially 180 degrees to edge supporting positions for either a stack of 10-inch or 12-inch records, the position 35 of the ledge 44 for 10-inch records being shown in full lines in Fig. 11, with its position for 12-inch records being shown in dotted lines.

With the records 23 thus supported at their center and edge, rotation of the eccentric ejector 40 portion 33 to a position out of concentricity with the centering pin 24 and into a position shown in Fig. 8 concentric with the cap 36, permits the lowermost record R in the stack of records 23 to drop about the ejector portion 33 and into a 45 center-supported position on the top of the bearing member 27. On the return of the ejector portion 33 to its position shown in Fig. 7, the lowermost record R is ejected or pushed from the top of the bearing 27 and from the ledge 44 into a 50 centering position relative to the pin 24 as indicated in dotted lines to permit its being dropped into a playing position on the turntable 16. When the ejector portion 33 is returned to its 55 position in Fig. 7, the next successive bottom record R' is supported directly thereon, its release into a playing position being accomplished in the same manner as above described for the record R. On the completion of the playing of all of the 60 records in the stack 23, the eccentric member 36 is manually moved to its position concentric with the pin 24, as shown in Fig. 9, whereby all of the 65 played records may be simultaneously removed from the turntable 16.

As previously mentioned the lower end 31 of the tubular member 28 of the ejector unit has a driving gear 32 mounted thereon. Rotation of the member 28 through a defined angular distance 70 to control the oscillatory movement of the eccentric portion 33 in the releasing of a record into a playing position, is accomplished by means of the bent operating arm 25 which is pivotally supported at the bend therein by axis means 43 mounted on the lower side of the top plate 15 (Fig. 1). One end 40 of the arm 25 is formed with

a segmental gear portion 45 in meshing engagement with the gear 32, its opposite end being provided with a roller or cam follower 47 operatively associated with a grooved cam track 48 (Figs. 1 and 12) formed in the lower side of a rotary cam unit 49, which is rotatable on a stub shaft 51 supported from the lower side of the mounting plate 15. As is clearly shown in Fig. 12, the cam track 48 is substantially symmetrical with respect to the cam diameter D so that the arm end 40 is moved through one complete oscillation in response to a rotation of the cam 49 of one revolution. Because of this oscillatory movement of the arm end 40 and its operative engagement with the gear 32, the ejector portion 33 is operated back and forth through a defined angular distance on each rotation of the cam 49, with the rest position of the cam corresponding to the position of the portion 33 concentric with the centering pin 24.

In the operation of the record changing mechanism for an automatic phonograph it is well known that the operation of the record releasing means usually occurs in a timed relation relative to the operation of the phonograph tone arm, so that the tone arm generally is in a position to one side of the turntable when an unplayed record is being placed thereon. In other words, on the completion of playing of a record, the tone arm is both lifted and moved outwardly from the played record before a new record is put into a playing position. The means in the present invention for accomplishing this predetermined operation of the tone arm is best shown in Figs. 1 and 14. The tone arm or pick-up unit 52 is rotatably supported on the mounting plate 15, by means designated generally as A, and is provided at its pivot or swinging point with a vertically movable lifting pin 53 having its upper end 54 in operative engagement with the tone arm pick-up unit so that a lifting of the pin vertically in turn lifts the pick-up unit from a record in playing position. Lowering of the pin, of course, lowers the pick-up unit into a playing position. The lower end L of the pin 53 is in riding engagement with a flat circular cam track 56 provided on the top side of the cam 49. The cam track 56 is formed with a gradually recessed or depressed portion 57 having a low spot 58 substantially centrally thereof, the positioning of the lower end of the pin 53 in the low spot 58 indicating a playing position of the tone arm 52. This position of the pin 53 and tone arm is shown in Figs. 1 and 14. Thus as the cam 49 is rotated relative to the pin 53, movement of the low portion 58 from under the pin 53 provides for a gradual lifting of the pick-up unit from the record in playing position, with the pick-up unit being retained in a raised position so long as the pin 53 rides on the flat surface of the cam track 56, the pick-up unit, of course, being lowered when the low spot 58 is again rotated thereunder.

The means providing for a pivotal swinging movement of the tone arm 52 includes a rocker arm 59 (Figs. 1, 14, and 15) mounted on the tone arm lifting pin 53 for pivotal movement concurrently therewith and having a portion 55 pivotally connected to one end E of a link or arm member 64 to be later described. A second end E' on the arm 64 oppositely arranged from the end E has a cam follower or roller 61 thereon operatively associated with an axially extending cam track 63 formed on the cam member 49. On rotation of the cam 49 engagement of the track 63 with the pin 61 pivotally moves the tone arm

52 in a predetermined direction against the pressure of a biasing spring 60, the cam tracks 56 and 63 being relatively arranged so that the pick-up unit 52 is held in a raised position by 5 the pin 53 when the tone arm is pivotally moved by the cam track 63.

The link member 64 at a third end 66 thereof is formed with a slot 67 having a pin 68 slidably movable therein (Fig. 15). The pin 68 is supported on a disc member 69, which in turn is mounted on the lower end of the shaft 46 of the record edge support, previously described. On rotation of the ledge 44 to a position for supporting either 10 or 12-inch records, the disc 69 is concurrently rotated to in turn actuate the arm end E' to change the position of the cam follower 61 relative to the cam track 63. These changed positions, as indicated in full and dot-dash lines in Fig. 15, are in correspondence with the size of 10 the records to be played and are defined by the engagement of a pivot P for a pivoted spring-pressed member 62 with corresponding oppositely arranged recesses 69A in the disc 69. It is apparent, of course, that the change in the position of the roller 61 changes its engaging position on the cam track 63 and hence the timed actuation of the tone arm in the record changing cycle of operation. By virtue of this assembly the pivotal movement of the tone arm 52 relative to 15 20 25 30 35 40 45 50 55 60 65 70 75 the outer edge of the turntable 16 is controlled in correspondence with the size of the records to be played.

From the above description and consideration of Figs. 1, 12 and 13, it is seen that all of the cam tracks 48, 56, and 63 are integrally formed on the single cam member 49 and are all arranged relative to each other so that on one complete revolution of the cam, after a record has been played, the tone arm is lifted and removed from 40 such played record prior to the actuation of the record ejector unit by the operating arm 25, and is lowered on the new record after it is in a playing position. Thus during the playing of a record the cam 49 is stationary, its rotation through one revolution occurring and being controlled, after 45 the record has been played, by the provision of means now to be fully described.

The cam 49 is formed with a peripherally extending rim 71 (Figs. 1, 12, and 13) having teeth 50 thereon in engagement with a gear 72 rotatable on a bracket unit 73 which is pivotally supported at one end on the cam shaft 51. The gear 72 in turn engages a pinion 74 mounted on one end of a shaft 76 rotatably supported in the bracket unit 73 and having a rubber gear 77 mounted at 55 its opposite end. The toothed rim 71, and gears 72, 74 and 77 are in continuous operating engagement, with the gears 72, 74 and 77 being pivotally movable concurrently with the bracket unit 73 about the cam shaft 51. The rubber gear 77 is frictionally engageable with the table rim 22, and movable into and out of engagement therewith on pivotal movement of the bracket unit 73. By virtue of the continuous engagement of the rubber gear 77 with the cam 49, it is clearly apparent that engagement of the gear 77 with the inner periphery of the table rim 22 immediately rotates the cam, so that the bracket and gear assembly serves as a clutch means for 60 65 70 75 operatively connecting the cam 49 in driven engagement with the turntable 16. It is evident from a consideration of Fig. 1, that the clutch means and cam means are arranged entirely below the mounting plate 15, with the rubber gear 77 being positioned above such plate and beneath

the turntable 16. Because of the relative assembly of these parts all of the record changing operating mechanism is concealed from view to provide for an overall neat construction and appearance of the phonograph.

As was previously described the changing of a record is entirely accomplished during the rotation of the cam 49 through one revolution. Since the cam is rotated when the gear 77 is in engagement with the table rim 22, it is apparent that the duration of this engagement controls directly the angular movement of the cam 49. To define the angular displacement of the cam 49 through one revolution and hence the selective engagement of the gear 77 with the table rim 22 there is provided means including a pair of relatively movable actuating or control arms 78 and 79 (Figs. 1-4) which are pivotally supported on a common axis 81 mounted in the top plate 15. Arms 78 and 79 are made by die casting with the arm 79 being of bent form with a hub 82 (Fig. 4) at the bend having a peripheral recess or cut away portion 83 at one end thereof of a predetermined angular extent. One end 84 of the arm 79 extends away from the cam 49 and has a pin 86 mounted thereon which is adapted to be inserted for slidable engagement in a slot 87 formed in a lug or projection 88 on the bracket unit 73. The opposite end 89 of arm 79 has a roller or follower portion 91 operatively engageable with an axially extending cam track 92 on the cam 49 (Figs. 1 and 13). The cam track 92 is of circular contour and formed with a low spot or recess 90 for a purpose to be later explained. The arm 79 is substantially straight longitudinally thereof and has a hub 93 at one end (Fig. 4) provided with an axially extending lug or stop portion 94 which is positioned within the recess 83 on the hub 82 of the arm 79. Thus when the arms 78 and 79 are in their assembled positions on the shaft 81, relative pivotal movement therebetween is limited by the engagement of the stop portion 94 with the sides S and S' of the recess 83. The end 95 of the arm 78 has a latch or locking portion 85 bent upwardly away from the cam 49 for releasably engaging a catch 80 formed on the leg 75 of a trip or crank arm 96 to be later described. Positioned inwardly from the latch portion 85 is a roller or cam follower 97 operatively engageable with a segmental cam track 98 formed integrally with the cam track 63 but projected upwardly therefrom, so that the roller 97 is engageable only with the segmental cam track 98.

From a consideration of Figs. 2 and 3, therefore, it is seen that the arm ends 89 and 95 diverge outwardly from each other and in a direction generally toward the periphery of the cam 49. These arm ends are yieldably connected together by a torsion spring 99 having the coils thereof positioned about the shaft 81, with one end 101 thereof connected to the end 89 of the arm 79 and its other end 102 connected with the end 95 of the arm 78. The spring 99 is arranged to bias the arm ends 89 and 95 to an inner relative position defined by the engagement of the stop 94 against the side S' of the recess 83, this inner position being shown in Fig. 2. A spring 103 is connected at one end to the mounting plate 15 and at its opposite end to the arm end 89 to apply a pressure thereon in opposition to the pressure exerted by the spring 99, for a purpose to be later explained. By virtue of the above described construction and assembly of the arms 78 and 79 it is apparent that the move-

ment of the end 89 of arm 79 correspondingly moves the opposite arm end 84 to in turn pivotally move the bracket 73 through the slot and pin connection 86-87 and hence the friction gear 77 relative to the table rim 22, this movement of the arm end 89 being dependent upon the position of the cam follower 91 on the cam track 92 and the action thereon and on the arm end 85 of the springs 99 and 103.

As was noted the latch 85 on the arm end 95 is adapted to be releasably locked with the catch 80 on the leg member 75 of the crank or trip arm 96. The crank arm 96 is pivoted on axis means 104 supported from the top plate 15. The leg member 105 of this arm has a serrated or toothed inner edge 106 for operative engagement with a pawl member 107 (Figs. 1 and 2) pivoted at the outer end of an arm 108, the inner end of which is connected with the tone arm 52 to provide for the arm 108 being pivotally movable concurrently therewith. The pawl member 107 is under the tension of a spring 109 which retains the pawl in position relative to the serrations 106. The pawl for a counter-clockwise movement of the arm 108 and hence of the tone arm 52, as viewed in Fig. 1, is free to ride or slide over the serrations 106. However, on movement of the arm 108 in an opposite direction, the pawl 107 engages one of the serrations 106 by virtue of the pawl having to pass through a dead-center position before it can ride over the serrations when moving in such reversed direction. Retention of the leg member 105 in an engaging position with the pawl 107, and of the catch 80 in a position for locking with the latch 85 on the leg member 78 is provided by a coil spring 111 connected at one end to the leg 75 and at its opposite end to the mounting plate 15.

In the operation of the actuating arms 78 and 79 let it be assumed that the parts of the record changing means are in their relative positions shown in Fig. 1, which positions occur when a record is being played, the arm ends 89 and 95 being extended apart to their outermost positions and the follower 91 being positioned in the cam recess 90. As the tone arm 52 moves inwardly on the record by virtue of its following engagement in the usual record grooves, the pivoted arm 108 is moved upwardly to the left or in a clockwise direction, as viewed in Fig. 1, with the pawl 107 riding over the serrations 106. This movement of the arm 108 continues until the tone arm 52 reaches the eccentric groove 112 (Fig. 1) at the center of the record, the outward movement of the tone arm 52 as produced by this eccentric groove moving the arm 108 in a reversed direction or to the right as viewed in Fig. 1, whereby the pawl 107 engages a serration 106. This engagement of the pawl 107 with a serration moves the leg member 75 of the crank arm 96 in a clockwise direction also as viewed in Fig. 1, to in turn trip the catch 80 to release the end 95 of the arm 78.

Since the arm ends 89 and 95 in their outermost extended positions are under an increased pressure by the spring 99 for movement to their innermost positions, the arm end 95, on release of the arm 78, moves in a counter-clockwise direction, as viewed in Figs. 1, 2, and 3, toward the arm end 89. Movement of the arm end 95 in this direction occurs by virtue of the pressure on the arm end 89 by the spring 103 in opposition to the pressure thereon by the spring 99. In other words, the action of the spring 103 tends to retain the arm end 89 against being moved by the

spring 99. When the spring 99 pulls the arm ends 89 and 95 to their relative inner position where the lug 93 engages the side S' of the recess 83, both arm ends 89 and 95 are concurrently moved in a counter-clockwise direction, as viewed in Fig. 1, by the spring 103. This counter-clockwise movement of the end 89 of the arm 78 in turn moves the opposite arm end 84 and the bracket 73 in a clockwise direction as viewed in Fig. 1, to frictionally engage the rubber gear 77 with the rim 22 of the table 16. Thus arms 78 and 79 and gear 77, immediately on the release of the arm end 95 by the trip arm 75, are moved to their relative positions shown in Fig. 2, with the follower 91 removed from the recess 90 and the gear 77 in driven engagement with the table 16, to rotate the cam 49 in a direction indicated by the arrow. These relative positions are maintained during the operation of the record releasing means and tone arm in the manner above fully described.

When the record changing operation is substantially completed the segmental cam portion 98 is rotated into engagement with the roller 97 on the arm end 95. Since the cam track 92 which is operatively associated with the roller 97 is of circular contour, the arm end 89 is retained thereby in a substantially fixed position at all times except when the roller 97 is opposite the recess 90. Thus with the arm end 89 maintained stationary by the cam 49, the arm end 95 is urged outwardly and away from the arm end 89 by the cam track 98 to a position at which the catch 88 on the trip arm 75 releasably engages the latch 85 on the arm end 95. It is clear, of course, that so long as the arm end 89 is retained stationary or in a substantially fixed position, this movement of the arm 78 occurs independently of any movement of the arm 79 so that the rubber gear 77 continues in engagement with the table 16. This engaged position of the gear 77 and the extended positions of the arm ends 89 and 95 away from each other and on locking of the arm 78 by the trip arm 75 is clearly shown in Fig. 3.

Since the cam 49 is rotating during the locking of the arm 78, the recess 90 in the cam track 92 continues to be moved toward the follower 91. When the recess 90 reaches a position opposite the follower 91 the tension in the spring 99, which has been increased by virtue of the moving of the arm ends 89 and 95 to their outermost positions, is sufficient to overcome the opposed pressure by the spring 103 so that the arm end 89 is moved in a clockwise direction as viewed in Fig. 1, and inwardly toward the arm end 95. This movement of the arm end 89 in turn pivots the arm end 84 and the bracket unit 73 in a clockwise direction, as viewed in Figs. 1 and 2, to disengage the rubber gear 77 from the turntable 16. On disengagement of the gear 77 from the table 16 the rotary cam 49 is stopped and the mechanism is returned to the starting position shown in Fig. 1. A positive control of the cam 49 for rotation through substantially one complete revolution for each cycle of operation of the record changing means is thus positively accomplished. On the completion of the playing of each record a similar operation of the mechanism occurs.

Modified forms of the actuating arms 78 and 79 are shown in Figs. 5 and 6, in which like numbers primed refer to the corresponding parts of the arms 78 and 79 as above fully described. The arms 78' and 79' are stamped from sheet metal, the arm 79' having a substantially flat triang-

ularly shaped body portion 129 and a pin 86' and a roller 91' at the ends 84' and 89', respectively, of the long side thereof, these ends being offset from each other laterally of the body portion 129 by virtue of the bend 131 therein. The third end 130 of the arm 79' is formed with a mounting or hub portion 132 comprising a substantially L-shaped extension integral with the body portion 129 and having one leg 133 extending laterally therefrom, with its other leg 134 positioned inwardly over the end 130 in spaced parallel relation with the body portion. Aligned apertures 135 are provided in the body portion 129 and leg portion 134 to receive an axis member or pin 81' which is carried by the base plate 15.

Arm 78' is also of substantially flat form with a longitudinally extending body portion 137 having an end 136 thereof bent inwardly in spaced relation with the body portion 137 to provide a mounting portion or hub portion for the arm 78' similar to the hub portion on the arm 79'. The body portion 137 and bent end 136 are formed with aligned apertures 135 to receive the axis pin 81'.

In the assembly of the arms 78' and 79' the leg member 135 is positioned between the body portion 137 and bent end 136 of the arm 78' with the pin 81' being extended through all of the apertures 135, the end 95' of the arm 78' being positioned outwardly from the body portion 129 such that the roller 91' on the end 95' is movable toward and away from the roller 91'. A tension spring 99' is connected at one end to a lug 140 provided at the end 89' of the arm 79', and at its opposite end to a lug 141 formed at the end 95' of the arm 78'. Spring 99' functions to continuously pull the arm ends 89' and 95' toward an innermost position defined by a lug or stop portion 142 punched or bumped out of the body portion 129 substantially centrally thereof, and in a position for engaging the arm 78' at its bent end 136.

In the assembly of the arms 78' and 79' relative to the above described clutch means, the pin 86' is inserted within the slot 87 (Figs. 2 and 3) with the spring 103 being connected to the arm end 89' by insertion of such end in an aperture 146 in the body portion 129. The end 95' of the arm 78' is integrally formed with a bent or catch portion 85' for operative engagement with the catch 88 of the crank arm 96. The operation of the arms 78' and 79' is similar in all respects to the operation of the arms 78 and 79 as has been fully explained.

Where it is desired to change or reject a record before it has been completed, or successively change records without being played, record reject means are provided which includes an actuating knob or button 113 (Fig. 1) which is arranged for manual operation in the top of the mounting plate 15 and in a position adjacent the motor starting switch 14. The actuating button 113 is in operative engagement with an operating arm 114 having slots 116 therein for slidably supporting the arm on pins 117 mounted on the underside of the top plate 15. A flat spring 115 of substantially right-angle shape has one leg 118 thereof secured to a supporting bracket 119 attached to the bottom of the mounting plate 15, the outer end 121 of the leg 118 being of arcuate form for slidable engagement with a cam block 122. The other leg 123 of the spring member is engageable with a lug portion 124 bumped out of the arm 114. The operating or outer end 126 of the arm 114 is bent upwardly

for engagement with a pin 127 on the leg 105 of the crank arm 96. As shown in Fig. 1 the record reject means is in an idle or rest position, the engagement of the spring leg member 123 with the lug portion 124 functioning to hold the upturned end 126 out of an engaging position with the pin 127. On actuation of the button 113 to operate the reject means, the operating arm 114 is moved downwardly, as viewed in Fig. 1, the engagement of the end 126 with the pin 127 pivotally moving the crank arm 96 in a clockwise direction, whereby to release the end 95 of the arm 78 from its locked engagement with the catch portion 80. Immediately on release of the arm 78, and regardless of the position of the tone arm 52 relative to the turntable 16, the record changing mechanism is operated in the manner above fully described. So long as the reject button 113 is held in an actuated position, the catch 80 on the crank arm 96 will be out of a locking position with respect to the end 95 of the arm 78, and the record changing means will continue in operation. On release of the reject button 113, the operating arm 114 is moved upwardly as viewed in Fig. 1 by virtue of the action of the spring 115, so that the end 126 is out of an engaged position with the pin 127. The catch portion 80 is thus returned to an engaging position with the arm 78 by the spring 111 so that the cam 49 is stopped after such locking engagement is accomplished in the manner above described.

From a consideration of the above description and drawings, it is seen that the invention provides for an improved record changing means which is simple and rugged in construction, easily adjustable, and compactly assembled for supporting from the top plate 15 of the phonograph. The entire assembly is comprised of but relatively few parts, a single cam being used to operate the tone arm and record releasing unit. The releasing unit is in operative engagement with the cam 49 directly through the oscillating arm 25 so as to eliminate the plurality of transmission parts usually connecting these elements. The pivoted clutch means for operatively connecting the rotary cam 49 in driven engagement with a continuously rotating turntable 16 is selectively actuated by mechanical means constructed and assembled to operate positively and precisely with but a minimum of adjustment. Because of the positive actuation of the clutch means and its positive retention in an operated position, only a relatively small pivotal movement thereof is required to accurately control the rotation of the cam 49. With the rubber wheel 77 positioned beneath the turntable 16 for engagement with the inner periphery of the rim 22, and the cam and clutch means located below the mounting plate 15 the operating mechanism is removed entirely from exposed positions on the top 15 and adjacent the turntable 16, to in all provide for a neat and pleasing appearance of the phonograph.

Although the invention has been described with reference to a specific embodiment thereof, it is to be understood that modifications therein can be made which are within the full intended scope of this invention as defined by the appended claims.

I claim:

1. In record changing mechanism having rotary cam means and including a driven wheel with movable supporting means and driving means for said driven wheel, with said driven

wheel mechanically associated with said cam means, the means for moving said driven wheel into and out of engaging position with said driving means to control the rotation of said cam means including a pair of coaxially pivoted actuating members, one of said members being connected with said movable supporting means, and each of said members having an end thereof associated with said cam means, with said one member on being pivotally moved in turn moving said driven wheel, tension means arranged to normally pull said two ends toward each other, other tension means connected with said one member to oppose the pressure applied thereon by said first tension means, and means including said cam means permitting relative movement between said two ends to provide for a selective movement of said one member by said two tension means.

2. In record changing apparatus including a rotatable operating member mechanically associated with driven means having movable supporting means and driving means for said driven means, the means for moving said driven means into and out of engaging position with said driving means to selectively control the operation of said operating member including a pair of relatively movable members each of which has an end portion associated with said operating member, and a third end portion on one of said pair of movable members connected with said supporting means and movable simultaneously with one of said two end portions, spring means arranged to move said two end portions toward each other to an inner position, yieldable means connected with said one end portion for exerting a pressure thereon in opposition to said spring means, said yieldable means, when said two end portions are in their inner position, being adapted to pivot said one end portion in a direction which moves said third end portion to move said driven means into engaging position with said driving means, means including said operating member for relatively spreading said two end portions apart against the pressure of said spring means, with said one end portion being retained in a substantially fixed position by said operating member to hold said driven means in said engaging position, and means releasably locking the other end portion in its spread position while said operating member permits said one end portion to be moved by said spring means in a direction which moves said third end portion to move said driven means out of said engaging position, and means for releasing said locking means on completion of the playing of a record.

3. In record changing mechanism having rotary cam means and driving means therefor, and including rotary means mechanically associated with said cam means and means supporting said rotary means for pivotal movement, the means for pivotally moving said rotary means into and out of engaging position with said driving means including a pivoted actuating member having one end connected with the pivotal supporting means for said rotary means, and its opposite end associated with said cam means, means pivotally supporting said actuating member intermediate said two ends so that pivotal movement of said opposite end in turn pivots said one end to pivotally move said rotary means, and spring means in engagement with said actuating member and cooperating with said cam means to selectively move said opposite end to provide for a

selective pivoting of said one end to actuate said rotary means.

4. In record changing apparatus having rotary cam means and a driving turntable, the means for selectively connecting said cam means and driving turntable including a driven wheel, mounting means for said wheel, and means associated with said cam means for moving said mounting means and said wheel therewith including a pair of relatively movable members, and tension means in engagement with said movable members cooperating with said cam means to move said mounting means.

5. Record changing apparatus as defined in claim 4 with said tension means including first spring means in engagement with one of said movable members, and second spring means common to said pair of movable members, said second spring means acting to yieldably pull said pair of movable members toward each other.

6. In record changing apparatus including rotary cam means and having an axially mounted driving turntable and a driven wheel with mounting means therefor, mechanical means for selectively actuating said mounting means to move said wheel into and out of engagement with said driving turntable, with said mechanical means constituting the sole means for moving said mounting means and including a pair of relatively movable pivoted arm members associated with said cam means and driven wheel mounting means, a common axis for said pair of arm members parallel to the axis of said turntable, and tension means in engagement with said arm members, with said tension means cooperating with said rotary cam means to pivotally move said arm members and actuate said mounting means.

7. A record changing apparatus having rotary cam means and a driving turntable, the means for selectively connecting said cam means and driving turntable including a driven wheel, mounting means for said wheel, means associated with said cam means and mounting means for moving said mounting means and said wheel therewith including a pair of relatively movable arms, said arms being of substantially flat form, with one of said arms having a body portion with a mounting portion at one end thereof comprising an L-shaped extension having one leg thereof positioned over said one end, with said body portion having a lug extending laterally therefrom, and the other of said arms having a body portion with one end thereof bent over in spaced relation with the body portion of said one arm to provide a mounting portion on said other arm corresponding substantially to the mounting portion on said one arm, said one leg on said first arm being arranged between the bent end and body portion of said second arm, with said bent end in an engaging position with said lug, axis means common to said two mounting portions, with pivotal movement of said two arms toward each other being defined by the engagement of said bent end with said lug, and tension means in engagement with said movable arms cooperating with said cam means to actuate said arms and move said mounting means.

8. In record changing apparatus including a driving turntable and cam means with said two elements being axially mounted with the axes thereof in a parallel relation, the means for selectively operating said cam means including a driven wheel associated with said cam means, means pivotally supporting said wheel, means for

actuating said supporting means to pivotally move said driven wheel into and out of engagement with said turntable including a pair of relatively movable arms associated with said cam means, with one of said arms being connected with said supporting means, axis means common to said pair of arms and parallel to the axes of said turntable and cam means, and spring means in engagement with said pair of arms, said spring means, cam means, and other of said arm members cooperating to selectively pivot said one arm to actuate said supporting means.

9. In record changing apparatus having rotary operating means and driving means therefor, and including movably supported rotary driven means operatively connected with said operating means, the means providing for a rotation of said operating means through substantially one complete revolution including a pair of pivoted members for moving said driven means into and out of engaging position with said driving means, axis means common to said two pivoted members for pivotally supporting the same, one of said pivoted members having a connector portion connected with said driven means to move the same, and an end portion associated with said operating means, and the other of said pivoted members having one end portion associated with said operating means, and spring means in engagement with said pivoted members cooperating with said operating means to move said driven means.

10. In record changing apparatus having rotary operating means and driving means therefor, and including rotary driven means operatively connected with said rotary operating means and movable into and out of engaging position with said driving means, the means for moving said driven means including a pair of relatively movable arm members, one of which arm members is connected at one end with said driven means, with its opposite end angularly spaced from an end of said second arm, spring means arranged to move said two angularly spaced arm ends toward each other, means including said rotary operating means for spreading said two arm ends apart, means releasably holding the one end of said second arm in a spread apart position while said rotary operating means permits the opposite end of said first arm to be moved in one direction by said spring means, the one end of said first arm in turn moving said driven means out of an engaging position with said driving means, means for releasing said second arm from said holding means when a record has been played so that said two arm ends may be moved together by said spring means, and yieldable means concurrently moving said two arm ends, and moving the one end of said first arm in an opposite direction to in turn move said driven means into an engaging position with said driving means.

11. In record changing apparatus having rotary cam means and a driving turntable with an axially extending rim portion, the means for selectively operating said cam means from said driving turntable including a driven wheel positioned below said turntable and inwardly of said rim portion, mounting means for said wheel, and means associated with said cam means for moving said mounting means and said wheel therewith relative to said rim portion including a pair of relatively movable members, and tension means in engagement with said movable mem-

bers cooperating with said cam means to move said mounting means.

12. In record changing apparatus having an operating member, and including a driving turntable and a movably supported driven wheel associated with said operating member, the means for selectively moving said wheel into and out of driven engagement with said turntable including a pair of coaxially supported pivoted members, each of which said pivoted members

has an end portion associated with said operating member, spring means acting on said pivoted members to move said end portions toward each other to an inner position, and other spring means for concurrently moving said pivoted members when said end portions are in said inner position, with said two spring means cooperating with said operating member to move said driven wheel.

10

RUDOLPH A. BECWAR.
